GAMEBOARD

Elizabeth W. Hawkins, R.F.D. 2,
Englishtown, N.J. 07726

Filed June 29, 1967, Ser. No. 7,649

Term of patent 14 years

(Cl. D34—5)

The figure is a plan view of a gameboard showing my new design. The board is of conventional thickness.

I claim:

The ornamental design for a gameboard, substantially as shown and described.
